UNITED STATES PATENT OFFICE.

HENRY RENO, OF PORTLAND, OREGON.

OIL-CAN HOLDER.

SPECIFICATION forming part of Letters Patent No. 423,631, dated March 18, 1890.

Application filed November 23, 1889. Serial No. 331,332. (No model.)

To all whom it may concern:

Be it known that I, HENRY RENO, a citizen of the United States, residing at Portland, in the county of Multnomah and State 5 of Oregon, have invented certain new and useful Improvements in Oil-Can Holders, of which the following is a specification.

This invention relates to oil-can holders of that class employing a stationary support and 10 a swinging can-holding frame; and it has for its object to provide a device of this character in which the empty can is quickly and readily extracted for the substitution of a filled can.

A further object of the invention is to provide a simple and improved can-holder possessing advantages in point of inexpensiveness, durability, ease of operation, and general efficiency.

In the drawings, Figure 1 is a perspective 20 view of a can-holder embodying my invention. Fig. 2 is a vertical longitudinal sectional view of the same. Fig. 3 is a top or plan view. Fig. 4 is a detail perspective view of the swinging frame, the can being removed. 25 Fig. 5 is a detail front elevation of the retaining-catch secured in position.

Corresponding parts in the figures are denoted by the same letters of reference.

Referring to the drawings, A designates 30 the stationary frame or support, which comprises two parallel vertical uprights or standards *a a*, having broadened lower ends, preferably cut away upon their under sides to form feet *a'*, upon which the frame rests. The 35 uprights or standards are connected by a cross-piece *a²*, preferably mortised therein to retain the uprights or standards in their relative positions.

B designates the swinging frame, which is 40 carried by the stationary frame or support and embodies in its construction two parallel vertical standards *b b'*, connected at their lower ends by a cross-piece *b²*, preferably secured thereto by mortises. The standard *b* 45 extends some distance higher than the standard *b'*, the purpose of which will be herein-after described, and between these standards, at about midway the former and near the upper end of the latter, is disposed a rectangular frame C. This frame is preferably formed of metal and cast into shape, and is

provided at two opposite corners with outwardly-projecting bearing-lugs *c c*, which pass through perforations therefor in the standards and bear in bearings *c' c'*, formed in the upper ends of the standards *a*. The corners of the frame C adjacent to the standards *b b'* are countersunk therein, at which points the frame is provided with perforations, through which are passed securing-screws *c²*, and said standards are provided at their inner opposing sides with V-shaped grooves *d d*, corresponding to the angle formed by the adjacent corners of the frame C, the inner surface of said corner angles being flush with the 65 walls of the grooves.

The frame just described is designed to hold a can D rectangular in cross-section, which, when in position, has its adjacent corners seated in the grooves *d*, the bottom of 70 the can resting upon the cross-piece *b²*.

To retain the can in place when the device is in use, I have provided a spring-catch E, disposed near the upper end of the standard *b* at its inner side and in such manner as to 75 prevent interference with the removal or insertion of the can. This catch has an inwardly-projecting shoulder *e*, adapted to engage the upper edge of the can, and from which projects outwardly an arm *e'*, the latter passing through a recess *e²*, provided therefor in the standard *b*. The upper end of the catch is provided with a vertically-elongated slot *f*, through which is passed a screw F for securing the catch to the standard. By means of 85 this slot the catch is adjustable to correspond with cans of various heights.

The operation and advantages of my invention will be readily understood by those skilled in the art to which it appertains. To 90 insert a can the same is turned with its spout to the front and the side corners are passed down the grooves *d*, the catch yielding sufficiently to permit of this, and when the top edge of the can has passed the catch the latter seeks its normal position. The can is thus 95 securely retained within the frame until the catch is operated to remove the same.

I claim as my invention—

1. In an oil-can holder, the combination, 100 with a stationary frame or support, of a swinging frame mounted therein and comprising

parallel standards provided at their inner opposite faces with grooves, and a spring-catch provided on one of said standards and adapted to retain the can within the frame, substantially as set forth.

2. In an oil-can holder, the combination, with a stationary frame or support, of a swinging frame mounted therein and comprising parallel standards having grooves extending along their inner opposing faces, forming guides for the can when inserted, substantially as set forth.

3. In an oil-can holder, the combination, with a stationary frame or support, of a can-supporting frame pivotally mounted therein and comprising a rectangular frame, parallel vertical standards secured thereto, and connected at their lower ends by a cross-piece forming a rest for the can, the standards being provided at their inner opposing faces

with grooves, forming guides for two opposite corners of the can, substantially as set forth.

4. In an oil-can holder, the combination, with a stationary frame or support, of a can-supporting frame pivotally mounted therein and comprising a rectangular frame, parallel vertical standards secured thereto at opposite corners and recessed to receive said rectangular frame, one of said standards being elongated, grooves in the inner opposing faces of the standards, forming guides for the can, and a catch disposed at the upper end of said elongated standard and adapted to retain the can in place, substantially as set forth.

In testimony whereof I affix my signature in presence of two witnesses.

HENRY RENO.
